WATCH BRACELET OR SIMILAR ARTICLE

Marc Huguenin, Geneva, Switzerland, assignor to Montres Rolex S.A., Geneva, Switzerland, a firm of Switzerland

Application September 23, 1958, Serial No. 52,731

Term of patent 14 years

(Cl. D45—4)

Fig. 1 is a top plan view of a watch bracelet showing my new design; and

Fig. 2 is a side elevational view thereof with the fastening device in open position.

I claim:

The ornamental design for a watch bracelet or similar article, as shown.
